(57) **CLAIM**

The ornamental design for a cutting body, as shown.

DESCRIPTION

FIG. 1 is a perspective plan view of an alternate embodiment according to the invention;

FIG. 2 is a perspective bottom view of the embodiment of FIG. 1;

FIG. 3 is a plan view of the embodiment of FIG. 1;

FIG. 4 is a bottom view of the embodiment of FIG. 1;

FIG. 5 is a side view of the embodiment of FIG. 1;

FIG. 6 is a front view of the embodiment of FIG. 1; and,

FIG. 7 is a rear view of the embodiment of FIG. 1.
